PLASTIC SHEET MATERIAL

John R. Ellefson, Newburgh, N.Y., assignor to E. I. du Pont de Nemours and Company, Wilmington, Del., a corporation of Delaware

Application November 13, 1958, Serial No. 53,361

Term of patent 14 years

(Cl. D87—3)

FIG. 1

FIG. 2

FIG. 3

Figure 1 is a plan view of the plastic sheet material showing my new design.

Figure 2 is an enlarged portion of the design shown in Figure 1.

Figure 3 is a cross sectional view taken on line 3—3 of Figure 2.

The new design is characterized by widely spaced annular dimple-like bas-relief portions enclosing alternate ridges and valleys on a background of fine grained substantially parallel striations.

I claim:

The ornamental design for a plastic sheet material, substantially as shown and described.
